UNITED STATES PATENT OFFICE.

FREDERICK NISHWITZ, OF MILLINGTON, NEW JERSEY.

HARROW.

SPECIFICATION forming part of Letters Patent No. 288,658, dated November 20, 1883.

Application filed July 21, 1883. (No model.)

To all whom it may concern:

Be it known that I, FREDERICK NISHWITZ, of Millington, in the county of Morris and State of New Jersey, have invented certain new and useful Improvements in Harrows, of which the following is a specification.

My invention relates to that class of harrows in which trailing curved cutters or teeth are carried upon gang-bars arranged transversely to across the line of draft, and on which several patents have heretofore been issued to me.

My present invention relates more especially, first, to an improved sulky organization of my machine; second, to certain improvements in the manner of connecting the draft-pole or tongue with the transverse cross bar or bars; and, third, to the manner of and devices for attaching the trailing cutting-teeth to the transverse gang-bars.

20 The details of the invention are fully set forth below.

In the accompanying drawings, Figure 1 is a rear perspective view of my improved sulky machine. Fig. 2 is a side elevation, partly in section, with the sulky-wheel indicated by dotted line. Fig. 3 is a detail top view of the tongue-connections and portions of the transverse gang-bars. Fig. 4 is a detailed bottom view of the tongue-connections and a portion 30 of the forward gang-bar. Fig. 5 is a detailed section on the line 5-5 of Fig. 3. Figs. 6 to 14, inclusive, are detail views of the devices for securing the harrow-teeth on the gang-bars.

In Letters Patent of the United States No. 35 262,308, granted to me August 8, 1882, I have shown a one-wheeled sulky-machine somewhat like that herein described. In that machine, however, the end of the axle was directly connected to a draft-beam or stock rigidly connected to the transverse gang-bar, and the 40 only vertical adjustment of the harrow was obtained by rocking the entire harrow-frame vertically by means of a lever and lifting-chain. The tongue of the machine was connected to 45 the sulky-frame and not to the harrow, and the driver's seat was carried by a seat-supporting standard secured on the sulky-frame.

The special form of harrow, *per se*, shown in 50 the present case is, so far as the general organization and operation are concerned, ex-

actly similar to the machine shown in Letters Patent No. 262,820, patented August 15, 1882.

In order to produce a sulky-machine in which the transverse gang-bars may be adjusted or rocked to vary the angular relation of the cutting-teeth to the soil, I connect the axle or cross-bar A of the sulky-machine to the top of the harrow-seat-supporting standard by means of a pin on the standard, which enters an eye, a', or socket, firmly secured on 55 the axle or cross-bar A. The driver's seat is mounted directly on the cross-bar A, and can be adjusted to the right or left by setting its securing-bolt in any one of a series of apertures, a, according to the condition of the soil 60 and according to the amount of weight it is desired to throw upon the cutting-teeth. By the construction thus described the driver, from his seat on the machine, may seize the lever of the harrow and vibrate or rock the 70 gang-bars and teeth to vary their relation to the soil or to free them from clogging-matter, as is fully set forth in my Letters Patent No. 262,820. For a complete description of this 75 operation of the harrow reference is made to that patent, and more detailed description here would merely be repetition.

To firmly couple the harrow and sulky-frame a brace-rod, b, extends from an eye on the seat-supporting standard, near its base, to 80 the cross-bar A. In this organization the draft-pole or tongue is secured to the harrow and not to the sulky-frame. A machine of this character will be found very efficient in light soil and in wet weather, where all the adjustments and vibrations of the teeth are necessary, but where the full weight of the driver 85 is not required on the machine.

The next part of my invention relates to the adjustable connection of the tongue or draft-pole with the transverse gang-bars. The draft stub or bar C is firmly braced by stay-rods c c, which extend from the forward gang-bar to about its middle. The operating-lever d is pivoted in the rear of this draft-stub, and is 90 connected by a link, e, with the seat-supporting standard, which is pivoted on the draft-stub and supported by pivoted uprights or rods f on the rear gang-bar, g. By this construction the draft frame or stub is firmly 95 100

united with the gang-frame. An angle-bar, E, curved in the arc of a circle, struck from a center, x, near the forward end of the draft-stub, is firmly bolted to the draft-stub near 5 its rear end, and the stay-rods c pass through apertures in its downwardly-projecting flange. The skeleton-tongue H, preferably formed of strips of angle-iron h, straddles the draft-stub, and is pivoted in the forward end of the draft- 10 stub, at the point x, by means of a cross-strap, h', joining the two side sections of the tongue. The rear ends of the tongue-sections, which diverge somewhat, rest upon the face of the curved angle-plate E, and are also connected 15 by a cross-strap, i, which extends under the draft-stub. Thumb-bolts I pass through the tongue-sections h, and are provided with enlarged heads or clamping-flanges i', which embrace the under side of the curved angle-bar 20 E. By loosening these bolts the tongue H may be turned on the pivot x to change its angular relation to the gang-frame, and may be clamped in any adjusted position by screwing up the thumb-bolts I, which will bind the 25 rear end of the tongue to the curved angle-bar E. The angle of the gang-frame and cutters to the line of draft may be changed to suit varying conditions of work, or the bolts may be left loose, so as to allow the parts of the 30 machine to play freely and seek their equilibrium, thus preventing the machine from shying.

The details of construction just described may be varied without departing from my invention.

The next part of my invention relates to means for securing the trailing teeth on the transverse gang-bars, and is illustrated in Figs. 6 to 14, inclusive.

40 Fig. 6 is a plan view, and Fig. 7 an edge view, of one of the securing plates or sockets for the short flat spurs k, which are carried on the forward gang-bar between the trailing teeth. These socket-pieces l are formed with 45 side flanges, l', on their under faces, between which the flat spurs k are inserted. Extensions l'' of the socket-pieces project along the upper faces of the spurs and serve to brace them against upward strain. The upper faces 50 of the socket-pieces are formed with transverse depressions, in which the washer-bar m, Fig. 3, which preferably extends the entire length of the gang-bar, is placed. The gang-bar, spurs, socket-pieces, and washer-plate 55 are firmly secured together by suitable bolts, l', Fig. 3.

Fig. 8 is a plan view, Fig. 9 an end view, and Fig. 10 a side view, of a somewhat similarly-formed socket-piece, n, for securing the 60 trailing cutting-teeth n' to the forward gang-bar. These teeth are formed with flat rearwardly-projecting shanks, which are preferably beveled or provided with a knife-edge on one side, so that when twisted they will 65 present a proper cutting-edge to the soil. The recess in the under side of the socket-piece n is shaped to correspond to this bevel of the

tooth, as clearly illustrated in Fig. 9. The socket-pieces are provided with transverse depressions for the reception of the washer-bar m, and are in other respects substantially the same as the socket-pieces represented in Figs. 6 and 7. The spurs and flat-tooth shanks on the forward gang-bar are so made as to constitute an open slotted crusher; but 75 on the rear gang-bar it is preferable to secure the teeth edgewise to the bar, so that their entire length will act upon the soil. Both gang-bars are preferably formed of angle-iron, as illustrated, and the rear gang-bar is 80 preferably arranged, as shown, with its interior angle turned down. The forward ends of the teeth o fit in this angular space, and are preferably snubbed or beveled off, as shown at o'.

85 The socket-pieces which hold the upper edges of the teeth are illustrated in Figs. 11 to 14, Fig. 11 being a top view, Fig. 13 a bottom view, Fig. 12 an end view, showing a section of the gang-bar, and Fig. 14 a side view, also showing a section of the gang-bar. The upper faces of these tooth-sockets p, which are clamped against the under face of the gang-bar, are provided with posts p' p', which fit into apertures in the gang-bar, and with ribs or lips p'', which fit against the rear edge of the gang-bar, as fully illustrated in Figs. 11 and 14. This construction holds the socket-piece firmly against any lateral or twisting movement. The under face of the socket-piece is 100 formed with a longitudinal recess, q, in which the upper edge of the tooth is secured by a hook-bolt, q', which passes through the gang-bar and socket-piece, its lower hooked end being inserted in an aperture in the tooth. 105 These are the primary peculiarities of structure. Further details of outline will be clear from the drawings, from which it will be seen that the rear projecting end of the socket-piece which contains the longitudinal recess 110 in which the tooth is held extends a short distance along the upper edge of the tooth and terminates in a point. A post or downwardly-projecting stud, r, is formed on the socket-piece close to the bolt-hole, and serves as a 115 lateral support to the tooth, which will be drawn against it by the strain of the hook-bolt. By means of these devices the cutting teeth and spurs are most permanently and 120 strongly united with the transverse gang-bars, and yet may be readily removed without difficulty. The eyebolts s on the upper face of 125 the rear gang-bar, which support the strut-rods f from the seat-supporting standard, are secured in socket-pieces t, which are provided with recesses for the reception of the bolts, which are rigidly clamped therein by a clamping-bolt having an enlarged washer which bears upon the shank of the eyebolt and holds it firmly. With this construction the eye-bolts may be shifted endwise, so as to project more or less in front of the gang-bar, as may be desired.

130 By the several improvements in structure

and organization above described a very efficient, strong, and easily-handled machine, which may be adjusted to suit all the varying conditions of soil, is produced.

5 I claim as my invention—

1. The combination, substantially as set forth, of the sulky-frame, the harrow connected with the sulky-frame by means of a rearwardly-projecting standard or seat-support on the harrow, a transverse gang or gangs of trailing cutting-teeth carried by the harrow, a lever for rocking the gangs to vary their angular relation to the soil independently of the sulky-frame, and with a movement independent of the tongue of the machine, and a driver's seat mounted on the sulky-frame.

2. The combination, substantially as set forth, of the sulky-frame, the harrow connected therewith by means of a standard or seat-support, the hinged transverse gang-bars, supporting-rod which support the sulky-frame on the hinged gang-bars, a lever for rocking the gangs to vary their angular relation to the soil, a driver's seat mounted on the sulky-frame, and means for shifting the seat laterally to vary the weight upon the gangs.

3. The combination, substantially as set forth, of the sulky-frame, the harrow flexibly connected therewith and having a draft-pole or tongue and hinged gang-bars carrying trailing teeth, supporting-rod which support one end of the sulky-frame on the gang-bar or bars, and a lever for rocking the gang-bars to vary the angular relation of the teeth to the soil.

4. The combination, substantially as set forth, of the one-wheeled sulky-frame, the harrow flexibly connected with the end of the sulky-frame, transverse gangs of trailing cutting-teeth, a lever for varying the angular relation of the teeth to the soil, a tongue, and mechanism uniting the gang-bars and the tongue, so as to permit the angle of the pole to be varied relatively to the gang-frame.

5. The combination, substantially as set forth, of a draft pole or tongue, a gang bar or bars arranged transversely to the line of draft, trailing cutting-teeth carried by the gang bar

or bars, means for elevating or depressing the teeth to vary their angular relation to the soil, and mechanism connecting the draft-pole and gang-bar, so as to permit the angle of the pole relatively to the gang-bars to be varied.

55

6. The combination, substantially as set forth, of the transverse gang-bar, the teeth carried thereby in a line across the draft of the machine, the draft-stub secured thereto, the pole or tongue pivoted on the draft-stub, so that its angle to the line of draft may vary, and the lever for elevating or depressing the cutting-teeth to vary their angular relation to the soil.

7. The combination of the forward gang-bar, the draft-stub secured thereto, the curved plate bolted to the rear end of the draft-stub, the skeleton or bifurcated tongue pivoted on the forward end of the gang-bar, so as to straddle the draft-stub, and mechanism for clamping the tongue to the curved plate secured on the draft-stub, so as to hold it at any desired angle.

8. The combination, substantially as set forth, of a gang-bar, a series of socket-pieces with recesses on their under sides for the reception of the teeth, transverse sockets on their upper faces for the reception of the gang-bar or bar-washer which extends lengthwise of the gang-bar, rearwardly-projecting extensions which brace the teeth against strains, and means for clamping the teeth, socket-pieces, washer, and gang-bar together.

9. The combination, substantially as set forth, of the tongue, the forward gang-bar hinged thereto, the rear gang-bar hinged to the forward gang-bar, a rearwardly-projecting standard mounted on the tongue or draft-pole, supporting-rod extending from the rearwardly-projecting standard to supports carried by the rear gang-bar, and means for adjusting such supports to cause them to project more or less from the front edge of the rear gang-bar.

In testimony whereof I have hereunto subscribed my name this 20th day of July, A. D. 95 1883.

FREDERICK NISHWITZ.
